(57) **CLAIM**

The ornamental design for a cleaning mop, as shown and described.

DESCRIPTION

1. Cleaning mop

1.1 : Front

1.2 : Back

1.3 : Left

1.4 : Right

1.5 : Bottom

The design is a cleaning implement with a sponge mop and foam protection surrounding the bottom of the pole; protection is sought for the sponge mop and foam protected part of the pole; protection is not sought for the rest of the pole which is not foam protected.
